PERCUSSION MECHANISM FOR CLOSURES

Harry M. Thomas, Bowling Green, Ohio, assignor
of one-half to Harry E. Graham, Cygnet, Ohio

Application September 7, 1935, Serial No. 39,535

6 Claims. (Cl. 109—6)

My invention relates to a mechanism for effecting a percussion with a container which may contain an explosive or expansible material to thereby effect the explosion or release of said material. The invention particularly relates to setting off a fulminate coincident with an unauthorized tampering with an opening mechanism or other parts of a closure, such as the door to a safe and the like. The invention is therefore readily applicable for igniting a shell containing noxious gases and effecting release of the same upon an attempt by a person to effect an unauthorized entrance through or opening of the closure.

The invention has for an object to provide means, preferably disposed within the closure, capable of actuating movement upon vibrations of the closure or a part thereof, to effect the explosion of a fulminating element. Another object of the invention is to provide a means associated with a closure locking means and adapted to effect an explosion of the fulminating element upon a slight dislodgment of a part of said closure locking means. Thus, the ignition of a gas shell by said fulminating element may be effected before material damage has been done to the closure or its locking means during an attempted illegal entry.

A still further object of the invention is to provide a member of some mass, by reason of which develops considerable kinetic energy in motion, disposed in vibratory receiving relation to the closure and in an operative relation to a releasing means for a firing pin whereby said firing pin is released when a blow is applied to the closure to set the said mass member in motion. Another and further object of the invention is to provide a shell igniting means of considerable efficiency, both as to structure and installation, and of a simplicity in parts and working as to require little attention and skill in its use.

The invention consists in other features and advantages which will appear from the following description and upon examination of the drawing. Structures containing the invention may partake of different forms and may be varied in their details and still embody the invention. To illustrate a practical application of the invention I have selected a percussion mechanism for closures embodying the invention as an example of the various structures and details thereof that contain the invention and shall describe the selected structure hereinafter, it being understood that variations may be made without de-

parting from the spirit of the invention. The particular structure selected is shown in the accompanying drawing.

Fig. 1 of the accompanying drawing illustrates a view of a longitudinal section of a conventional door to a safe and shows a position of preferred installation of a percussion embodying my invention. Fig. 2 illustrates a view of an enlarged longitudinal section of the percussion mechanism shown in Fig. 1. Fig. 3 illustrates a face view of a part of the mechanism embodying my invention.

A mechanism which embodies the features of my invention has a member disposed for vibratory movement with reference to a firing pin release element and so as to actuate said release element on movement of said member. The force by which said member may be moved may be transmitted by a part or the body of the particular closure to which the mechanism is applied. Thus, should one forcefully apply a hammer or mallet to the closure or its part, the vibration set up by such a blow causes movement of the said member and resultant release of the firing pin.

In the particular mechanism shown in the accompanying drawing, a housing 1 is provided in and on which the elements and members of the mechanism are supported. The housing 1 may be supported, as by suitable bolts 3, on a cover plate 4 of a recess 5, commonly provided in a safe door 6. As is well known, the recess 5 permits access to the case 7, housing the well known operating and combination discs, for the purpose of changing the combination by which the door may be subsequently opened. The case 7 is usually formed of sheet metal and its bottom is stamped to form a boss 8 to bear one end of the disc-operating spindle 9. The spindle 9 extends outwardly through the door and is commonly provided at its other end with a dial handle 10, by means of which the combination and operating discs may be actuated. Thus, by necessity of construction, a point of weakness in the door 6 is provided and to which one seeking entry by unauthorized means often refers and attacks. The attack usually is in the form of an effort to drive the spindle 9 into the door until the operating disc is freed and accessible for operation with other tools. An attack of this character, whether successful or not in its result, causes material damage to the safe and often renders it unfit for subsequent use. It is therefore desirable to combat such an attack immediately upon the first blow thereof.

In the preferred form of mechanism, there is

provided a bolt 11 which is slidably mounted with reference to a plate 12, having an open-ended guiding boss 14 through which the bolt slides. The plate 12 is preferably mounted on the plate 4 and may be supported by the bolts 3, on the opposite side of the plate 4 from that on which the housing 1 is mounted. The bolt 11 has a massive portion 15 and coaxial shank portion 16. The shank portion 16 extends through an opening 17 formed in the plate 4 and into the housing 1. A suitable spring 18 is located on the shank portion 16 and is of a tension insufficient to move the bolt when it is at rest but sufficient to keep the bolt moving when it is moving toward the case 7 to cause the bolt to locate the end of the massive portion 15 against the bottom of the case 7 and preferably against the boss 8 thereof. One end 5 of the spring 18 may bear against the plate 4 and the other end bear against the massive portion 15. Thus, it will be seen that should one apply a blow to the dial handle 10 or its associated end of the spindle 9, the force thereof would be transmitted through the bottom and boss portion 8 of the case 7 to the massive portion 15 of the bolt 11, causing the same to move away from the case 7 and toward the housing 1.

As the bolt moves toward the housing 1, the shank portion 16 thereof engages and operates a trigger member 20. The trigger member 20 is supported for slight pivotal movements within the housing 1. As shown in the drawing, the trigger member has a goose-neck portion 21 which fits in an opening 22 formed in a sleeve 23 enabling pivotal movements of the trigger about said goose-neck portion 21. The sleeve 23 extends from within the housing 1 to a point outside thereof and may be locked in position with reference to the housing by a suitable set screw 24. The sleeve 23 may have a slotted portion 25 for guiding the trigger member 20 in its movement. An opening 26 is formed in the sleeve through which a catch extension 27 of the trigger member extends.

If desired, a suitable band spring 28 may be mounted, as by bolts 29, within the housing 1 and bear resiliently against the trigger member 20 to yieldingly maintain the catch extension within the opening 26. Thus, as the bolt 11 moves toward the housing 1, the shank portion 16 engages the member 20 and moves it against the bias of the spring 28 to withdraw the catch extension 27 from the opening 26 and thereby release a firing pin 30.

The firing pin 30 has a head 31 and a shank 32 and is supported for slidable movements within the sleeve 23. The shank portion has a notch 34 which is adapted to be engaged by the catch extension 27, when the notch is in registration with the opening 26. The firing pin is caused to move, during operation, by means of a high compression spring 35 which may bear at one end against the head 31 and at the other end against an annular shoulder 36 formed within the sleeve 23. It will be seen that the pin 30 may be moved 65 against the compression of the spring 35 until the notch 34 is engaged by the catch extension 27 of the trigger member to thus prime the mechanism for later firing by actuation of the trigger member, as described.

70 The particular mechanism described herein is particularly adaptable to igniting and causing a gas shell to burst, although those skilled in the art will appreciate other elements may be ignited or caused to explode. Gas shells are commonly 75 exploded by a fulminator, commonly known as

a bouchon, which is pictorially illustrated at 37.

The bouchon is supported in a skirted bushing 38, the skirt portion being telescopically insertable over the sleeve 23 to thus locate the bouchon in a direct line with the head 31 of the firing pin 30. The bushing 38 has threaded portions 40 which are adapted to be threaded into threaded portions 41 of a gas shell casing 42. The casing 42 may be mounted on the door 6 in any suitable manner. Suitable lock-out means may be provided for preventing accidental explosion, and if desirable, the skirt portion of the bushing 38 may be provided with aligned and diametrically opposed openings 45 through which a barrier, such as a pin, not shown, may be inserted to block the firing pin from striking the bouchon upon an accidental release of the firing pin in the normal and authorized use of the door 6.

While in accordance with the provisions of the statutes, I have illustrated and described the best form of my invention now known to me, those skilled in the art will readily understand that many changes may be made in the form of the mechanism disclosed without departing from the spirit of my invention as set forth in the appended claims.

I claim:

1. In combination with a safe door having a handle operated locking means, a gas shell percussion mechanism therefor comprising a housing mounted on the door, a weighted bolt movably supported with reference to the housing and disposed in contact with a part of said locking means, a firing pin movably mounted on the housing, a spring for moving the said pin, and a trigger member adapted to engage said firing pin when said spring is in compression and movably supported on said housing in a position relative to said bolt whereby the trigger member will be engaged by the bolt to release the firing pin when the bolt is moved away from said position of contact with said locking means.

2. In combination with a lockable closure having a handle operated locking means, a percussion mechanism comprising an actuating element movably supported in the closure and disposed in contact with the handle operated locking means whereby the actuating element is caused to move when a blow is applied to the said locking means, a percussion element movably supported on the closure, and a movable member adapted to engage said percussion element to hold the same against movement and disposed to be engaged by said actuating element when the same is moved in response to a blow on said locking means whereby the percussion element is released.

3. A percussion mechanism for a closure having a locking means comprising a housing means supported on said closure, a bolt supported for endwise movement with reference to said housing means and disposed in contact with a part of said locking means, a firing pin movably supported by said housing means, a spring disposed in bearing relation to said firing pin and adapted to move the same when compressed and a trigger element for engaging said firing pin and holding the same against movement and disposed in said housing means whereby the bolt will engage said trigger element and move the same to release said firing pin when the bolt is moved by a relative movement of said locking means.

4. A percussion mechanism for a closure comprising the combination of an actuating element supported in contact with said closure and susceptible of movement upon application of a blow

to the closure, a percussion element movably supported within the closure, means tending to move the percussion element, and a movable element adapted to engage said percussion element and hold the same against movement and disposed relative to the actuating element as to be engaged and moved thereby to release the percussion element.

5. In combination with a closure having a hand operated locking means, a gas shell percussion mechanism comprising a housing, a firing pin movably supported by said housing, a compressible spring for moving the firing pin, a trigger movably supported within the housing and adapted to engage and hold the firing pin from movement, a spring connected to the housing and pressingly engaging the trigger to yieldingly maintain the same in engagement with the firing pin, and a trigger actuator slidably supported on

the closure in force transmitting relation to the closure locking means and adapted to move and engage said trigger to release said firing pin, upon an application of a force on said locking means in an inward direction with respect to the closure. 5

6. In combination with a closure, a percussion mechanism comprising a frame, a percussion element movably supported on the frame and normally urged to move in one direction, a movable member for resisting said urgency of said percussion element, and a weighted element slidably supported in contact with said closure and adapted to engage said movable member when a blow is applied to said closure to thereby release said percussion element and permit the same to move in the said one direction. 10 15
